ANCHOR FOR INSERT PUMPS

Leon L. Mackowski, Bradford, Pa., assignor to Oil
Well Supply Company, Dallas, Tex., a corpora-
tion of New Jersey

Application March 11, 1938, Serial No. 195,394

1 Claim. (Cl. 166—1)

This invention relates to an anchor means for an insert pump for oil wells. An insert pump is adapted to be inserted within a string of tubing installed within a well casing and is usually provided with means to locate the pump at any desired depth within the tubing. Such means as have heretofore been provided for locating the pump within the tubing is illustrated by the invention described and claimed in Mack Patent No. 1,722,102 issued July 23, 1929, wherein a packing member is expanded into sealing relation with the inner surface of the tubing by means operated by the axial rotation of the sucker rods suspendingly supporting the said insert pump within the tubing, the said means operating also to provide a frictional engagement or gripping of the inner surface of the tubing at a point below the seal which functions to carry the weight of the said insert pump. One of the disadvantageous features of the particular means described and claimed in said Patent No. 1,722,102 is that during operation of the insert pump after being so located by the means provided in accordance with this patent the motion of the plunger tends to dislodge the gripping means and the packer seal thereby becomes broken, necessitating relocating and resealing of the said pump by the means provided.

One of the objects of the present invention is to provide an anchor means adapted to be dependingly supported below the packer means which will operate to restrain the dislodging of the gripping and sealing means provided for locating the pump in the tubing. Another object is to provide means adapted to be attached to the lower end of the plunger barrel of the insert pump which will operate to restrain axial movement of the barrel after locating the pump at the desired depth without unduly interfering with axial movement of the tubing while inserting, withdrawing, seating or relocating the pump within the well. Other objects and advantages will be apparent as the invention is more fully disclosed.

In accordance with these objects, I have devised a frictional spring anchor and means to dependingly support the same from the packer sealing off the area between the bottom of the insert pump and the string of tubing, of which the following taken in connection with the drawing is a full and complete disclosure.

In the drawing, Fig. 1 is a side elevational view of the present invention in combination with the invention of said prior patent and ready for insertion into tubing extending within a well cas-

ing. Fig. 2 is a sectional view of the combination illustrated in Fig. 1, as it appears located in operative position within tubing extending within a well casing. Fig. 3 is an enlarged sectional view of one feature of the present invention; and Fig. 4 is a section along plane 4—4 of Fig. 2.

Referring to the drawing (Figs. 1 and 2), the structure below line A—A illustrates the present invention, whereas the structure above illustrates the invention of said prior Patent No. 10 1,722,102, in combination with which the present invention is utilized. The structure above line A—A has been identified as to its main operating parts by suitable legends. For better understanding of the same, reference should be made 15 to the description and drawings of the said patent.

Briefly stated, the present invention consists in dependingly supporting frictional spring anchor means B from the bottom of coupling member 6 20 of the prior art structure above line A—A, known in the art as a cage slip assembly, by swivel joint means J, and in the specific structure of the swivel joint means J and the anchor means B. Swivel joint means J is essential to provide for 25 the unlocking and locking of the cage slip assembly above line A—A when locating or relocating the assembly within the tubing T disposed within well casing C, without axial disturbance or dislocation of the anchor means B. 30

The specific structure of swivel joint J is illustrated in Fig. 3. The bottom end of coupling member 6 is threaded and a collar 7 is threaded thereon and pins 8 securely hold the same against rotation to provide an annular shoulder for loose coupling member 9 which is provided with a complementary annular shoulder 10 adapted to engage the shoulder formed by collar 7 on coupling 6. An anti-friction washer 11 is interposed between the engaging shoulders to facilitate the 35 axial rotation of coupling 6 relative to coupling 9. The inner surface of the bottom end of loose coupling member 9 is threaded for the threaded engagement therewith of the threaded end of length of pipe 12. A coupling 13 connects a 40 second length of pipe 14 with pipe 12 forming at the same time an annular shoulder which is utilized as a stop for the means B as will be herein-after described.

With the structure illustrated in Fig. 3 it may 50 be noted that the cage slip assembly structure above line A—A may be rotated axially to operate the gripping and sealing means of the assembly without transmission of this rotating movement to pipe 12 and the assembly below line A—A. At 55

the same time the assembly below line A—A is dependingly supported from coupling member 6 of the assembly above line A—A.

Frictional spring anchor means B comprises a plurality of arcuate spring members B, the one end of each member being attached by means of screws 15 to collar 16 which is secured to the pipe 14 by means of three screws 17 uniformly spaced around the collar 16. The opposite end 10 of each spring member B is centrally located in a longitudinal recessed section of one section of a longitudinally split collar 18 and is held in position in the recess by rivets 19. The several sections of the split collar 18 are secured around an 15 extension length of pipe 20 joined to pipe 14 by coupling 21 in such manner as to frictionally engage the surface of pipe 20 with the springs B bowed outwardly sufficiently to frictionally engage the inner side walls of well tubing T. The 20 arrangement of springs B permits vertical movement relative to the string of tubing incident to the locating, relocating, insertion or withdrawal of the plunger barrel of the pump within T, but the frictional engagement of springs B against 25 the side wall tubing T anchors the plunger barrel of the insert pump against vertical up and down movements tending to break the seal provided by sealing means S, during operation of the said insert pump.

From the above description and drawing it is apparent that many modifications and adaptations may be made in the present invention without departure from the nature and scope as may be included within the following claim.

What I claim is:

In combination, a string of tubing for supporting an insert pump, expansible and contractible packer means to seal the insert pump tubing to the inner wall of said tubing and anchor means 10 dependingly and rotatably supported by and from said packer means to permit rotation of said packer means without dislodgement of said anchor means, said anchor means comprising a plurality of arcuate spring members, each having 15 one end secured to a collar member detachably secured to a length of pipe dependingly supported from the end of said packer by a connection allowing relatively free rotation of the packer about its axis, the opposite ends of the said spring members each being secured to a segment of a split collar member, and means to assemble the several said segments together and to hold the same in frictional engagement with the said dependingly supported length of tubing. 25

LEON L. MACKOWSKI.
